Primary Examiner — Mimosa De(74) Attorney, Agent, or Firm — Leanne Taveggia Farrell; Westman, Champlin & Koehler, P.A.(57) CLAIM

The ornamental design for a furnishing, as shown and described.

DESCRIPTION

FIG. 1 is a perspective view of a furnishing;
FIG. 2 is a side view thereof, the opposing side being identical;

FIG. 3 is a front view thereof, the rear being identical; and,
FIG. 4 is a top view thereof.

The broken lines shown in the drawings are included for purposes of illustrating portions of the furnishing and form no part of the claimed design.
